UNITED STATES PATENT OFFICE.

EDWARD F. SMITH, OF LOS ANGELES, CALIFORNIA.

ROTARY TOOTHBRUSH.

Application filed June 1, 1927. Serial No. 195,851.

My invention relates to a device for cleaning the teeth by brushing and it has particular reference to a simple and economical power driven brush which may be conveniently inserted into the mouth and by which a thorough cleaning of the dentition and removal of accumulations between the teeth may be effected.

The objects of the invention are to provide an inexpensive tooth brushing device in combination with a driving or rotating mechanism therefor, to provide a simple device of this character in which the brush employed may be conveniently replaced, and to provide a convenient support for the brush by which the flesh in the mouth will be protected against the brush during the operation thereof. These and other objects are accomplished by the device which I have illustrated in preferred form in the accompanying drawing, in which

Fig. 1 is a plan view of the device embodying my invention;

Fig. 2 is a sectional elevation, and
Fig. 3 is a detail of a polishing unit.

My invention consists in a broad sense of a power driven flexible shaft to which is connected a rigid shaft carrying a chuck, a housing for the rigid portion of the shaft, which forms a handle, and a brush mounted on a rod or shaft, the shaft having one end secured in and by said chuck, and the other end mounted in a bearing carried by said housing.

In a more specific sense, the invention comprises a flexible shaft 1, which includes in its assembly such shaft, a rigid shaft 2, connected with said flexible shaft, and a casing 3 within and relative to which said shafts 1 and 2 are rotatable. Arranged for detachable association with said casing 3 is a housing 4, forming a handle for the user of the device. This housing 4, as seen, is preferably made in two parts 4^a and 4^b, the part 4^a being provided with an internal bored bearing 5, which projects beyond the end of said part 4^a, and the part 4^b being fitted over the projecting end of said bearing 5 and arranged to be locked therein and in snug engagement with the end of said part 4^a by any suitable means, as by bayonet connection. Through the bore 5' of said bearing 5 is extended a stem 6, which at one end is arranged for interfitting detachable connection with the end of said rigid shaft 2.

For the purpose of co-operating for rotation with said shaft 2, the latter is provided with a key 7 that is arranged to fit in a longitudinal slot 6' in said stem. The connection of the rigid shaft 2 and the stem 6 is insured and the longitudinal displacement of said stem 6, when the part 4^b is disconnected from the part 4^a, is prevented, by a set screw 6" projecting through the part 4^a of the housing 4, through the bearing 5, and into a circumferential groove 5" provided in said bearing 5. The other end of said stem 6 is provided with longitudinal externally threaded spaced fingers 8 which, by means of a nut 9 engaging the threads on said extensions 8, are arranged to be pressed toward one another and to grip an article interposed therebetween. The fingers 8 in conjunction with the nut 9 constitute substantially a chuck, and this term is used herein to indicate the gripping end of the stem 6. The part 4^b of the housing handle 4 is formed or provided with an outwardly directed guard portion 10, of curviform cross section, and the end of said guard portion 10 is bent at substantially right angles thereto to provide a bearing for one end of the shaft 11' of a brush 11. The other end of said shaft 11' is arranged to be secured in said chuck, and access to nut 9 of the chuck assembly for tightening the fingers 8 upon said shaft 11' is afforded by oppositely disposed openings 12 in said part 4^b. In order to hold stationary the shaft 2, and the parts connected therewith, during the adjustment of the nut 9 for operating the fingers 8 into engagement or disengagement with the brush shaft 11', I provide a stop 13 which is mounted on the end of a spring member 14 secured on the outside of the part 4^a of the housing 4. This stop 13 extends through an opening in the wall of said part 4^a, and is arranged to be pressed into the slot 6' in said stem 6, whereby the rotation of said stem 6, and the parts associated therewith will be prevented, it being understood that the adjustment of said nut 9 must occur while the motor is at rest.

The guard portion 10, referred to, is, as stated, provided to support the free end of the shaft 11' of the brush 11, which is of longitudinal extent equal substantially to the length of an ordinary tooth brush; but, in addition to that function, it serves to

protect the flesh of the mouth from bristles during the operation of cleaning the teeth. For this purpose the guard is curviform and exposes only so much of the bristle area as 5 is needed. As shown in the drawing, this guard portion 10 is preferably an integral part of the tubular housing part 4^b and is preferably bent beyond the exterior longitudinal plane of the part 4^b for the purpose 10 of accommodating a brush larger than the diameter of said part 4^b would otherwise permit. The brush 11 described herein, may be replaced by a buffer, such as shown at 15, Fig. 3, or by any other device.

15 What I claim, is:

1. In a device of the character described, 20 a housing forming a handle and provided at one end thereof with a guard, a shaft within said housing and rotatable relatively thereto, a bearing within said housing, 25 a stem extending through said bearing and removably conjoined at one end with said shaft and at the other end provided with a chuck, means engaging said stem to prevent disengagement thereof with said shaft, a brush journaled at one end in said guard and having its other end secured in said chuck, said housing having openings through which access may be had to said

chuck for manipulating same and means to 30 operate said shaft.

2. A rotary tooth brush comprising a housing forming a handle and provided at one end thereof with a guard, a shaft within said housing and rotatable relatively thereto. 35 a gripping means provided on the end of said shaft, a brush journaled at one end in said guard and at the other end arranged for engagement by said gripping means, and means to hold the shaft against rotation during the operation of said gripping means. 40

3. In a device of the character described, a housing provided at one end thereof with a guard, a shaft within said housing and rotatable relatively thereto, said shaft provided with a key, a stem associated with said shaft for rotation therewith, said stem having a longitudinal slot through which the key of said shaft extends whereby the shaft during the rotation thereof may move longitudinally relative to said stem, a gripping means on said stem, a brush journaled at one end in said guard and having its other end secured in said gripping means, and means to operate said shaft. 50 55

In testimony whereof I have set my hand.

EDWARD F. SMITH.
